(57) **CLAIM**

The ornamental design for a freestanding ladder storage rack, as shown and described.

DESCRIPTION

FIG. 1 is a front perspective view of a first embodiment of a freestanding ladder storage rack showing my new design; FIG. 2 is a right side view of FIG. 1; FIG. 3 is a left side view of FIG. 1; FIG. 4 is a front view of FIG. 1; FIG. 5 is a rear view of FIG. 1; FIG. 6 is a top view of FIG. 1; FIG. 7 is a bottom view of FIG. 1; FIG. 8 is a cross-sectional view of the freestanding ladder storage rack of FIG. 1 with a removable shelving end cap; FIG. 9 is a front perspective view of a series of freestanding ladder storage racks of FIG. 1 holding a ladder and PVC piping.

FIG. 10 is a front perspective view of a second embodiment of a freestanding ladder storage rack showing my new design;

FIG. 11 is a right side view of FIG. 10;

FIG. 12 is a left side view of FIG. 10;

FIG. 13 is a front view of FIG. 10;

FIG. 14 is a rear view of FIG. 10;

FIG. 15 is a top view of FIG. 10;

FIG. 16 is a bottom view of FIG. 10;

FIG. 17 is a cross-sectional view of the freestanding ladder storage rack of FIG. 10 with a removable shelving end cap; and,

FIG. 18 is a front perspective view of a series of freestanding ladder storage racks of FIG. 10 holding a ladder and PVC piping.

Applicant notes that the markings on the drawings are for shading purposes only, and are not to be considered a part of the design of the present invention.

The broken lines depict portions of the article and environment that form no part of the claimed design.
